UNITED STATES PATENT OFFICE.

JEFFERSON B. BRACKETT, OF WALES, ASSIGNOR TO HIMSELF AND ARCHIE L. TALBOT, OF LEWISTON, MAINE.

WRINGER-SUPPORTER FOR WASH-BENCHES.

SPECIFICATION forming part of Letters Patent No. 245,697, dated August 16, 1881.

Application filed November 19, 1880. (No model.)

To all whom it may concern:

Be it known that I, JEFFERSON B. BRACKETT, of Wales, of the county of Androscoggin and State of Maine, have invented a new and useful Improvement in Wringer-Supporters for Wash-Benches; and I do hereby declare the same to be described in the following specification, and represented in the accompanying drawings, of which—

10 Figure 1 is a side elevation, and Fig. 2 a transverse section, of a wash-bench and its adjustable wringer-supporter containing my improvement.

In carrying out my invention I combine with 15 the bench a wringer-supporter having devices or means of enabling it to be moved lengthwise of the bench, and fixed or clamped in position thereon, as occasion may require; and, furthermore, I construct the said wringer-supporter 20 with one of its standards jointed to the top rail, such being to facilitate the adaptation of the supporter to, or its removal from, the bench.

In the drawings, A denotes a folding wash-bench, of which *a a* are its two outermost top 25 bars, and B the wringer supporter, this latter being composed mainly of two vertical standards, *b b'*, and a top rail, *c*, arranged as represented. This top rail is firmly secured to one 30 of the standards and jointed to the other, the joint-pin being shown at *d*, the same being so as to enable one standard to be moved away from or toward the other.

A plate, *f*, bent at a right angle, is fastened to each of the standards at its lower parts and 35 on its outer side, and provided, as shown, with two clamp-screws, *g*, which screw vertically through its horizontal portions, extending underneath one of the top bars, *a*. The standards at their lower ends rest on the said bars 40 *a a*.

From the above it will be seen that by means of the clamp-plates and screws the two standards may be fastened to the top rails of the

bench, which may be effected by screwing up the screws against the lower sides of such rails. 45 On loosening the screws the whole wringer-supporter may be slid along on the bench, so as to bring the said supporter at the middle, or nearer to one end than to the other of such bench, as circumstances may require, it being 50 sometimes inconvenient to have the supporter permanently fixed to the bench, either at the middle or near one end of such bench. By having one of the standards jointed to the top rail the standard may be so moved relatively 55 to its fellow as to admit of the two being moved laterally either into or out of engagement with the top bars, *a a*, of the bench. Each clamp-plate may have to it one or more clamping-screws, one being generally sufficient. 60

The top rail, *c*, is provided with a series of holes, as shown at *h*, such being to receive the joint-pin and to admit of the adjustment of the standard nearer to or farther from its fellow, in order to adapt the supporter to benches varying in their widths. 65

I do not claim a wringer-bench having the sustaining-standards of its wringer-supporting cross bar tenoned or fixed to the bench so as to be incapable of adjustment lengthwise of 70 the bench.

What I claim as my invention is as follows, viz:

The wringer-supporter, substantially as described, consisting of the two standards and 75 their clamping devices at their lower ends, and of the top-rail permanently fastened to one of the standards and jointed or connected to the other, as set forth, so as to admit of the latter standard being moved relatively to the former, 80 essentially as and for the purpose specified.

JEFFERSON B. BRACKETT.
